DENTAL PLATE

Eugen Kaczmarek, Berlin-Hermsdorf,
GermanyApplication January 9, 1933, Serial No. 650,903
In Germany January 9, 1932

4 Claims. (Cl. 32—3)

The present invention relates to dental plates, more particularly to a valve embodied in such plates for fixing the same in the mouth of the wearer, and has for one of its main objects to provide a dental plate valve capable of exhausting the air accumulating in the space between the roof of the mouth and the plate when the latter is placed in position, whereby a suction will be created therebetween to draw the plate and retain the same in proper position.

Another important object of the invention resides in the provision of a dental plate valve constructed to resist the action of saliva, thereby making it possible to materially increase the period of usefulness of said devices; the improved device being further constructed in a manner that the parts may be readily and easily replaced should for some reason they become deteriorated.

The invention also aims to provide a device of the character mentioned which will not depend, alone, upon the differences of pressure existing on either side of the device to operate the same, because this necessitates too great a suction between the palate and plate, thereby causing pains and inconvenience to the wearer, but wherein the action of the valve is assisted by positive means such as a spring urging the relative associated parts of the device into operative position.

It is likewise among the desired features of the invention to provide a valve for retaining dental plates in position, and which is so constructed that its proper functioning is assured regardless of the amount of air imprisoned within the space between the plate and palate.

Other important objects and advantages of the invention will be in part obvious and in part pointed out hereinafter.

In order that the invention and its mode of operation may be readily understood by those persons skilled in the art, I have in the accompanying drawing and in the detailed description based thereupon set out a possible embodiment of the same.

In the drawing:

Figure 1 is a face elevation of the valve plate; Figure 2 is a section through said plate showing the parts associated therewith;

Figure 3 is a face elevation of the valve base;

Figure 4 is a section through the valve plate itself; and,

Figure 5 is a section taken through the entire device.

Having more particular reference to the drawing wherein like characters of reference will designate corresponding parts throughout, my im-

proved device may be stated to comprise a valve plate *c* preferably of circular configuration, having a plurality of circular openings *f* formed therein, and provided with a rivet *g* or the like fixed centrally thereof with a portion extending laterally from one of its faces and terminating with a locking head *h*.

Positioned over the valve plate *c* and covering the openings *f* thereof, is a rubber cap *d* having a curled marginal edge snugly engageable with the adjacent portion of said plate, the cap lying over that face of the valve plate from which extends the rivet *g*, and, for that purpose, being provided with an aperture receiving said rivet.

Arranged over the valve plate *c* and its cap *d*, is a valve base *a*, likewise formed with an aperture for accommodating the extended portion of the rivet. A plurality of kidney shaped openings *m* disposed in registering relation with the openings *f* of the valve plate *c* are cut into said base. A series of apertures *n* are further provided upon the marginal peripheral portion of the valve base *a* serving as anchor means when affixing the valve by the ordinary vulcanizing process or otherwise to the dental plate of any well known construction.

A rubber disk *e* may be and is preferably inserted between the adjacent surfaces of the valve plate cap *d* and valve base *a* to assure the proper functioning of the valve as will be more fully described hereinafter.

The valve plate *c* with its rubber cap *d*, the rubber disk *e* and the valve base *a* are secured together by means of a flat spring *b* attached upon the outer surface of said valve base, arranged radially thereof and engageable with the locking head *h* of the central rivet *g*. In this manner, it will be understood that, by action of the spring *b*, the valve parts associated as hereinbefore described, will be pressed against one another and thus securely fit in their relative positions.

In using my improved device, the air enclosed in the space between the roof of the mouth and the surface of the dental plate, escapes through the kidney shaped openings *m* in the valve base *a* and passes out between the valve base *a* and the rubber disk *e*, thus creating a reduced pressure within said space. This causes the normal pressure upon the opposite or outer side of the dental plate, to act through the openings *f* of the valve plate *c* upon the rubber cap *d* thereof and force the rubber disk *e* into the kidney shaped openings *m* of the valve base *a*, therefore, hermetically closing the same and maintaining the pressure.

- reduced pressure created in the chamber or face between the palate and dental plate, thus fixing the latter in proper position within the mouth of the wearer.
5. The flat spring *b*, it will be understood, being locked to the head *h* of the securing rivet *g*, also acts to increase and assure the pressing of the rubber cap *d* and disk *e* against the opening in said valve base *a*.
10. Because the openings in the valve base *a* are given a kidney shaped configuration, it will be appreciated that registering relation with the circular openings *f* of the valve plate *c* is made positive even if said valve base and valve plate are accidentally or otherwise displaced relatively to one another.
- Manifestly, the construction shown and described is capable of considerable modifications and those modifications which come within the 20 scope of the claims, I consider within the spirit of the invention.
25. What I claim is:—
1. A suction valve for dentures comprising a valve base having openings therein, a valve plate arranged below said valve base and having openings therein adapted to register with the openings in said base, spring means arranged to urge said plate against said base and a resilient body interposed between said plate and base and adapted to be first gripped between the same and subsequently the registering portions of said body being extruded into the openings in said base by the pressure below said plate.
2. A suction valve for dentures comprising a 30 valve base having openings therein, a valve plate arranged below said valve base and having openings therein adapted to register with the openings in said base, spring means arranged to urge
- said plate against said base and a resilient body interposed between said plate and base and having a curled marginal edge arranged to engage the periphery of said plate, and adapted to be first gripped between the same and subsequently the registering portions of said body being extruded into the openings in said base by the pressure below said plate.
3. A suction valve for dentures comprising a base plate having elongated openings therein, a valve plate, a resilient cap member and a resilient disk member both interposed between said base and valve plates, spring means arranged to urge said valve plate against said resilient members and said base plate, said valve plate having 15 vent openings arranged to register with the openings in said base plate to permit external pressure to extrude said resilient members into the openings in said base plate.
4. A valve for fixing a dental plate in position 20 within the mouth of the wearer, comprising a valve plate having openings formed therein, a valve base arranged over said valve plate and provided with openings positioned in registering relation with the openings in said valve plate, means connected to said valve plate to maintain the same in position over the valve base, spring means associated with said valve plate and arranged to resiliently urge said valve plate against said valve base and a resilient body interposed 25 between said valve plate and said valve base whereby external pressure against said valve plate will act through the openings therein directly against said resilient body to compress portions of the same into the openings in said valve base.

EUGEN KACZMAREK.
